LIQUID MEASURING DEVICE

Michael J. Zwosta, Brooklyn, N. Y.

Application September 5, 1935, Serial No. 39,347
6 Claims. (Cl. 225—5)

This invention relates to a device designed and adapted to measure quantities of liquid, such as beer, and to automatically stop the flow thereof after a desired quantity has been delivered into a suitable receptacle or container provided for its reception.

The device is useful in conjunction with faucets and spigots of tapping systems, which faucets and spigots are disposed at a bar, counter, and the like where the beverage is dispensed.

The principal object of the invention is the provision of a device of the indicated character which makes it unnecessary to continually adjust or set the same because of a difference in the weight of various liquid receptacles or containers, such as pitchers, cartons, cans, buckets, pails, and the like.

Some of the advantages of the device are that the parts may be readily attached for use, and which may be readily detached so that a faucet or spigot may be used in the usual manner. A device which will be simple, inexpensive, and positive and reliable in operation and not liable to get out of operation in use.

The nature of the invention and its distinguishing features and advantages will appear when the following specification is read in connection with the accompanying drawing, in which—

Figure 1 is a view illustrating the invention in use, parts thereof being shown in section;

Figure 2 is a section showing the valve means of the faucet;

Figure 3 is a top view of the Siamese distributor attachment;

Figure 4 is a view of one of the weights used to measure different quantities of the liquid.

The invention is shown in the present instance in use in conjunction with a conventional faucet 10 constituting a part of a tapping system as is used for drawing off beer. It is to be understood that the invention may be employed in conjunction with any other suitable type of spigot or draw-off means. The faucet 10 includes a rocker 11 and a valve element 12 which is moved by the

rocker 11 on and off of a seat 13 to control the flow of liquid or beer through the downwardly turned discharge nozzle or outlet 14. A handle 15 is connected with the rocker 11 and may be manipulated to operate the rocker 11 for the purpose stated.

By moving the handle 15 forwardly, the valve element 12 will be moved off of the seat 13 allowing the liquid to flow through the nozzle 14. When the handle 15 is moved rearwardly the valve element 12 will be moved into engagement with

the seat 13 thereby stopping the flow of liquid.

In Figure 2 of the drawing the valve element 12 is shown in its open position.

In accordance with the invention, use is made of an attachment 16 which may be readily attached to the nozzle 14 of the faucet 10 and also be readily detached therefrom. This attachment is designed and adapted to deliver liquid into two receptacles simultaneously at different rates of flow in different directions at different points of reception. The attachment 16 is designed and adapted to deliver two streams of the liquid, and therefore may be aptly termed a Siamese attachment. The attachment 16 embodies a collar 17, an outlet end 18, and an outlet tube 19. The collar 17 carries a set screw 20, and has an interior shoulder 21. The collar is large enough to fit on the extremity of the discharge nozzle 14 of the faucet 10, the shoulder 21 limiting the insertion of the nozzle extremity and the set screw 20 serving to engage the nozzle 14 to securely hold the attachment 16 in place with the tube 19 projecting rearwardly. The attachment 16 applied to the nozzle 14 diverts the liquid leaving the nozzle 14 so that one stream will flow downwardly out of the outlet 18, and another stream laterally and then downwardly out of the outlet tube 19. The inner end of the tube 19 is notched, and said notched end 22 projects into the outlet end 18 transversely thereof as shown in Figures 1 and 3. The attachment 16 is so designed that three times the amount of liquid flowing out of the tube 19 will be flowing out of the outlet end 18.

In accordance with another feature of the invention use is made of a receptacle holder and means for attaching it to the rocker 11 of the faucet to stop the flow of liquid when a predetermined quantity of liquid has been distributed by the attachment 16. Accordingly, there is provided a holder 23 on the lower end of an off-set connecting rod 24 which has a hook 25 on its upper end engageable in a hole in the outer end of an arm 26 connected with the rocker 11. Use is made of a receptacle in the form of a drinking glass 27 of standard weight and size for holding approximately one-fourth of a pint of liquid by weight. The empty glass 27 is placed in the holder 23 while the latter is connected with the arm 26 and will enable the handle 15 to be moved forwardly to open the faucet allowing the liquid to flow until the glass 27 is almost filled with liquid whereupon the rocker 11 will be moved to close the faucet thereby stopping the flow of liquid. In this connection, it is to be observed that the weight of the handle 15, when the lat-

ter is in its forward position, and the friction of the movable parts of the valve, offer resistance to the weight of the holder 23, rod 24 and the glass 27.

- 5 With the attachment 16 applied to the nozzle 14 of the faucet 10, and the glass 27 in the holder 23, and a suitable receptacle or container 28 under the outlet end 18, when the handle 15 is moved forwardly, the valve means will be operated allowing liquid to flow through the faucet 10 to be diverted by the attachment 16, part of the liquid flowing through the tube 19 into the glass 27 and part of the liquid flowing through the outlet end 18 into the pitcher 28 placed below said outlet end 18. When three times the amount of liquid delivered into the glass 27 has been delivered into the pitcher 28, the holder 23, rod 24 connected therewith, and arm 26 will move downwardly under the weight of the liquid in the glass 27, thereby causing the rocker 11 to move, and the rocker 11 in turn causing the valve element 12 to move into engagement with the seat 13 to stop the flow of liquid through the faucet 10. The contents of the glass 27 is then poured into the pitcher 28 making a full pint of liquid or beverage in the pitcher 28. Thus, the device herein described measures the amount of liquid and at the same time stops the flow thereof. While the device in the present instance is described as measuring a full pint, it is to be understood that suitable means such as the weight 29 shown in Figure 4 may be used by placing the same in the holder 23 to measure various other quantities of the liquid.

35 I claim:

1. A liquid measuring device comprising means to deliver liquid into two receptacles simultaneously, a valve to control the flow of liquid, said valve having manually operable means to move the same to open position, and means on which one of said receptacles may be positioned, said last means being suspended from said manually operable means to operate the latter to stop the flow of liquid when a predetermined quantity of liquid has been delivered into said receptacle thereon.
- 40 2. The combination with a faucet, of a Siamese liquid distributor connected with the outlet of the faucet, a receptacle holder, and a rod having one end connected with said holder and its other end connected with the flow control means of the faucet, said holder adapted to hold a receptacle in position to receive a predetermined quantity of liquid from the faucet, said receptacle and rod constituting means operable through the weight 45 of the receptacle and the liquid therein to close the flow control means.

2. The combination with a liquid discharge control device having means for discharging streams at different points simultaneously, of a

receptacle holder suspended from said device so as to stop the discharge of liquid when a predetermined quantity of liquid from one of said streams has been discharged by said means into a receptacle placed on said holder.

3. The combination with a liquid discharge control device, of a Siamese liquid distributor connected with the outlet of said device in order to divert the liquid leaving said outlet so that one stream will flow downwardly and another stream laterally and then downwardly from said outlet, and a receptacle holder connected with said device to operate the latter so as to stop the discharge of liquid when a predetermined quantity of liquid from one of said streams has been discharged by said distributor into a receptacle placed on said holder.

4. A distributor for connection with a main fluid outlet, consisting of a collar constituting a supplemental outlet, means for removably attaching the distributor to said main outlet and a tube of appreciably less diameter than the outlet, extending across the outlet, and having an opening in its wall in the outlet, said tube constituting a supplemental outlet connected with 25 said collar.

5. A distributor for connection with a main fluid outlet, consisting of a collar constituting a supplemental outlet, means for removably attaching the distributor to said main outlet and 30 a tube also constituting a supplemental outlet connected with said collar, the inner end of said tube which is of less diameter than the outlet projecting into said collar and being notched so that some fluid leaving said main outlet may 35 flow through said collar and come into said tube.

6. The combination with a faucet, of a Siamese liquid distributor connected with the outlet of the faucet, a receptacle holder, and a rod having one end connected with said holder and its other 40 end connected with the flow control means of the faucet, said holder adapted to hold a receptacle in position to receive a predetermined quantity of liquid from the faucet, said receptacle and rod constituting means operable through the weight 45 of the receptacle and the liquid therein to close the flow control means.

MICHAEL J. ZWOSTA.
